UNITED STATES PATENT OFFICE.

JOHN W. DARLEY, JR., OF BALTIMORE, MARYLAND, ASSIGNOR TO THE WM. KNABE & CO. MANUFACTURING COMPANY OF BALTIMORE CITY, OF BALTIMORE, MARYLAND, A CORPORATION OF MARYLAND.

PIANO-ACTION FRAME.

No. 872,292.

Specification of Letters Patent.

Patented Nov. 26, 1907.

Original application filed September 11, 1905, Serial No. 277,989. Divided and this application filed February 6, 1906, Serial No. 299,813. Renewed September 10, 1907. Serial No. 392,215.

To all whom it may concern:

Be it known that I, JOHN W. DARLEY, Jr., a citizen of the United States, residing at Baltimore city and State of Maryland, have 5 invented certain new and useful Improvements in Piano-Action Frames, (this application being filed as a division of my pending application, Serial No. 277,989, filed September 11, 1905, for a combined manually 10 and mechanically operated piano;) and I do hereby declare the following to be a full, clear, and exact description of the invention, such as will enable others skilled in the art 15 to which it appertains to make and use the same.

This invention relates to piano-actions, more particularly the action-rails and supporting brackets for piano-actions composed of mechanisms or groups of instrumentalities mounted upon or attached to superimposed action-rails; as in modern 20 upright pianos, wherein the hammer, its wippen or rocker, the jack and associated devices are mounted on an upper rail, while 25 the abstract or wippen-actuating rod is pivotally-attached to a lower rail.

The main object is to provide for structure and arrangement of the whole piano-action in two distinct but properly correlated or 30 organized mechanisms, adapted to be separately introduced into or taken from the instrument, with a view to simplifying and facilitating the construction, assemblage and adjustment of the instrument, and permitting 35 the removal or separation of parts without deranging the respective mechanisms.

A further object is to provide for nicety of adjustment of the action rails, of insuring 40 precision in the relation and arrangement of the respective mechanisms, bringing the hammer and its wippen in proper relation to the abstract and to the key.

The invention will hereinafter be fully 45 described with reference to the accompanying drawings, which form a part of this specification, and then more particularly pointed out and defined in the appended claims.

50 Figure 1 is a fragmentary front view of the interior construction of an instrument embodying my invention, showing the action-rails and their supporting brackets,

and showing one element only of the piano-action associated with one key, the same 55 being represented near the left of the figure which is also broken away at the middle for compactness of illustration. Fig. 2 is a vertical cross-section taken through the piano-action at the right of the extreme right-hand 60 action-bracket and looking toward the left or opposite end of the instrument. Fig. 3 is a similar section taken through the action at the right of one of the intermediate brackets, and looking in the same direction. 65 Fig. 4 is a detail side view of one of the lower outer brackets of the lower action rail; it being noted that the two action rails are attached to separate brackets which are respectively superimposed one above the 70 other. Fig. 5 is a plan view of the bracket shown in Fig. 4. Fig. 6 is a detail plan view of the lower arm of one of the intermediate brackets. Fig. 7 is an enlarged detail perspective view of a non-rotatable nut 75 which fits in a slot in said arm of the upper intermediate bracket, and is used in connection with the adjusting of the upper bracket with respect to the subjacent lower bracket. 80

A particular explanation of the illustrated construction is as follows:

1 denotes the piano-case; 2 the bed or wood bottom of the key-board; 3 the keys (only one key with its associated element of 85 the piano-action being shown in Fig. 1, also in Figs. 2 and 3). As well understood, the key when depressed by the performer's finger lifts the abstract or vertically-disposed wippen-actuating rod 4, which actuates the 90 wippen or rocker 5 to cause the hammer 6 to strike upon the string 7.

There are two action-rails, an upper and lower one, designated by the numerals 8 and 9 respectively. The hammer 6 and associated devices for producing its stroke and recoil are supported by the upper action-rail 8, the hammer being actuated as usual by its wippen 5 which is pivotally-attached to the under side of the action-rail. The abstract 100 4, which transmits motion from the key to the wippen, is shown pivotally attached to and supported by the lever 10 and link 11, which are themselves pivotally attached to and supported by the lower action-rail 9. 105 The upper end of the abstract, shown having

an adjustable cap 12, bears under the wippen but is not positively connected thereto, so that the upper action-rail and group of instrumentalities supported thereby is a distinct and separable mechanism from the lower action-rail with the abstract attached thereto. In this case, the illustrated piano-action is designed for incorporation in an autopneumatic instrument (shown and described in my aforesaid application, Serial No. 277989), wherefore the abstract is shown supported by the key by means of the adjustable capstan-screw 13 at the rear end of the key-lever taking under the front end of the lever 10, which extends slightly beyond its pivotal connection with the abstract or wippen-actuating rod 4; while the abstract is shown vertically-disposed behind the rear end of the key-lever and adapted to be supported and liftable by the pneumatic striker (not shown); so that the hammer can be actuated either from the key or striker, the abstract being not positively connected with either agency. This particular feature however is not part of my present invention but is described only for explanation of the illustrated construction, it being understood of course that the invention herein described and claimed is susceptible of embodiment in or with instruments of other construction and operation.

The action-rails 8 and 9 are independently mounted one above the other, longitudinally of the piano-case, said rails being attached to separate and distinct upper and lower brackets, there being for each rail two outside or end brackets and preferably two intermediate brackets, the upper brackets being superimposed above the corresponding lower brackets. These brackets are designated as follows: The lower rail 9 is attached to and supported by the outer or end brackets 14 and intermediate brackets 15. The upper rail 8 is attached to and supported by the superimposed outer or end brackets 16 and intermediate brackets 17. The lower brackets 14 and 15 rest upon and are secured to the bed 2 of the key-board. The upper outside brackets 16 are supported on posts or bolsters 18, screwed into and projecting up from the key-board bed 2. Said posts or bolsters pass up through slots or openings 19 in the feet of the lower outside brackets 14, permitting adjustment of said brackets transversely of the key-board, it being well understood that such provision for adjustment is practically essential in view of possible slight inaccuracies in the castings of the metal brackets. Said posts or bolsters 18 are shown surmounted by balls 20 engaged or seated in cups or sockets 21 at the lower parts of the superimposed upper outside brackets 16; thus providing adjustable bearings for the upper outside brackets, the vertical adjustment being obtained by screwing the

bolsters up or down in the wood bottom 2 below the key-board, the lower portions being threaded for that purpose.

The upper intermediate brackets 17 are adjustably mounted on the subjacent lower intermediate brackets 15, the specific means illustrated being as follows: The tops of said lower intermediate brackets 15 are shown surmounted by balls 22 engaging or seated in cups or sockets 23 adjustably-attached to the feet or lower arms of the upper brackets 17 so as to accommodate adjustment of said subjacent brackets 15 transversely of the key-board, corresponding to the similar adjustment of the lower outer or end brackets 14 before explained. Said cups 23 are shown at the lower ends of threaded stems or bolts 24 which are tapped or screwed in non-rotatable nuts 25 (one of said nuts being shown enlarged in Fig. 7). Said nuts 25 are adjustable along the feet or lower arms of the upper brackets 17, the said nuts having reduced portions 26 slidable in slots 27 in the feet or lower arms of said brackets 17, said slots 27 extending transversely of the key-board and action-rails. The bolts or threaded rods 24 are also provided with jam-nuts 28, for securing the bolt in proper position after it has been adjusted. Thus it is observed that the cups 23 are capable of both vertical adjustment and horizontal adjustment transversely of the key-board. The several upper brackets, both the outer ones 16 and intermediate ones 17, are further attached at their upper parts to the interior back frame of the instrument by means of the usual headed screws 29 entered through the upper ends of said brackets and into the projecting studs or posts 30. Proper disposition or arrangement of the upper outside brackets 16 is afforded by adjusting the bolsters or posts 18, and proper disposition of the upper intermediate brackets 17 is afforded by adjusting their lower cups 23; and the upper ends of the several upper brackets are held by the screws 29 to the posts 30, which are set at the proper projection from the back-frame of the instrument.

The foregoing explains the manner of mounting the upper and lower parts of the action. In constructing the piano, the lower part of the action, comprising the lower action-rail 9 with its attached brackets 14 and 15 and the abstracts pivotally-connected to the rail, is first mounted in the instrument, the supporting brackets 14 and 15 being fastened on the bed 2 of the key-board in such position as to locate the abstracts or wippen-actuating rods 4 in correct position relative to the keys. The upper part of the action, comprising the upper action-rail 8 with its attached brackets 16 and 17 and the several hammers and coöperating groups of instrumentalities carried by the upper action-rail, is then mounted in the instrument,

the upper outside brackets 16 being placed upon the bolsters 18 and the intermediate brackets 17 upon the intermediate lower brackets 15; and the posts 30 and also the 5 balls and cups 20 and 23 being properly adjusted, to bring the upper part or division of the action into proper relation with the key and the correlated mechanism of the lower part of the action.

10 The lower intermediate brackets 15 are shown having box-like portions 15^a therein, providing passages through the brackets transversely of the key-board. These boxings are intended for the passage of groups of 15 tracker-bar pipes or pneumatic tubes in the autopneumatic instrument, and this feature is not concerned in my present invention, being described merely to explain the peculiar form of the intermediate lower brackets as 20 shown. The arms 15^b shown projecting from the boxings 15^a, and shown broken away just above the boxings, are intended to extend upwardly to provide a support for the music-roll mechanism in the upper front 25 of the case, this also being a feature not concerned in the present invention.

Having thus fully described my invention, what I claim as new and desire to secure by Letters Patent of the United States is:—

30 1. In a piano, the combination of a piano-action comprising separate action-rails and superimposed groups of operative instrumentalities respectively connected to said rails, brackets supporting the lower rail, super- 35 posited brackets supporting the upper rail, said upper and lower brackets being relatively adjustable, thereby allowing horizontal adjustment of said lower brackets transversely of said rails without change of position of said upper brackets.

2. In a piano, the combination with the key-board bed, of an action comprising separate action-rails and superposed groups of operative instrumentalities connected to the 45 respective rails, brackets for the lower rail mounted on the key-board bed, bolsters or posts rising from said bed through slots in the feet or bases of lower brackets, thus permitting horizontal adjustment of the latter 50 transversely of said bed and rails, and brackets for the upper rail detachably mounted on said bolsters.

3. In a piano, the combination with the key-board bed and back-frame, of an action 55 comprising separate action-rails and superimposed groups of operative instrumentalities respectively carried thereby, brackets mounted on said bed and supporting the lower rail, bolsters or posts rising from said 60 bed through slots in the bases or feet of lower brackets permitting adjustment thereof transversely of said bed and rails without obstruction from said bolsters, and superposed brackets supporting the upper rail 65 having adjustable ball-and-socket bearings

on said bolsters and having their upper ends attached to said back-frame.

4. In a piano, the combination of a piano-action comprising superimposed groups of operative instrumentalities and separate action-rails therefor, supporting brackets for the lower rail, and superposed supporting brackets for the upper rail having vertically-adjustable ball and socket bearings on brackets supporting the lower rail.

5. In a piano, the combination with the key-board bed, of an action comprising superimposed groups of operative instrumentalities and separate action-rails therefor, supporting brackets for the lower rail, superposed supporting brackets for the upper rail mounted on lower brackets and having bearings on said lower brackets horizontally-adjustable in a direction transverse of said key-board and rails.

6. In a piano, the combination of a piano-action composed of upper and lower groups of operative instrumentalities and separate action-rails therefor, supporting brackets for the lower rail, superposed supporting brackets for the upper rail mounted upon lower brackets and having ball and cup bearings on said lower brackets, which bearings are vertically-adjustable and also horizontally-adjustable transversely of the key-board and rails to conform to the positioning of the lower brackets.

7. In a piano, the combination with the key-board bed and back-frame, of a piano-action composed of upper and lower groups of operative instrumentalities and separate action-rails therefor, each action-rail having independent supporting brackets, there being outside or end brackets and intermediate brackets, the lower brackets being mounted on the key-board bed, bolsters rising from said bed through slots in the bases of the lower outside brackets to permit adjustment of the latter transversely of said bed and rails, the upper outside brackets resting on said bolsters, the upper intermediate brackets resting on the lower intermediate brackets and having bearings thereon which are adjustable transversely of said bed and rails to conform to the positioning of said lower intermediate brackets corresponding to the positioning of the lower outside brackets, and the upper brackets being attached to the back-frame.

8. In a piano, the combination of two superimposed action-rails for adjustment of different parts of the piano-action, a supporting bracket attached to the lower rail, a superposed supporting bracket attached to the upper rail and mounted upon said lower bracket, there being a horizontally and vertically-adjustable ball and socket bearing for the upper bracket on said lower bracket.

9. In a piano, the combination with the key-board bed, of an action having separate

- supporting rails, a lower bracket attached to the lower rail and secured on said bed, said bracket having a slot or opening in its foot, a vertical post or bolster secured in said bed 5 and projecting up through said slot, an upper bracket attached to the upper rail mounted on said bolster, the slot in the foot of the lower bracket allowing adjustment thereof transversely of the key-board.
- 10 10. In a piano, an action comprising superimposed groups of operative instrumentalities, separate action-rails therefor, the lower group comprising an abstract or wippen-actuating rod, and links pivotally-con-

nected to said abstract and pivotally-at- 15 tached to the lower and upper sides of the lower action-rail, one of said links having a lever extension beyond its pivotal connection with the abstract, and a key-lever operating under said lever extension for lifting 20 the abstract.

In testimony whereof I affix my signature, in presence of two witnesses.
